ELECTRICAL COIL.

1,345,484.

Specification of Letters Patent. Patented July 6, 1920.

Application filed January 29, 1919. Serial No. 273,732.

To all whom it may concern:

Be it known that we, ARTHUR W. FISHER and CLARENCE S. SNAVELY, citizens of the United States, residing at Wilkinsburg and Pittsburgh, respectively, in the county of Allegheny and State of Pennsylvania, have invented certain new and useful Improvements in Electrical Coils, of which the following is a specification.

10 Our invention relates to coils of wire for use in electrical apparatus, such as magnets, relays and the like, and has for an object the provision of a novel and useful method for constructing such coils on flangeless tubes or 15 cores.

We will describe one method embodying our invention, and will then point out the novel features thereof in claims.

In the accompanying drawing, Figure 1 20 is a view showing in side elevation one form of finished coil constructed in accordance with our invention. Fig. 2 is a view showing in end elevation the coil shown in Fig. 1. Fig. 3 is a longitudinal sectional view 25 taken on the line III—III in Fig. 2. Fig. 4 is a fragmental sectional view of the coil shown in the preceding views, taken on the same section line as Fig. 3, and showing the coil in uncompleted condition, this view being on a larger scale than Fig. 2 to illustrate 30 more clearly the method of constructing the coil. Fig. 5 is a view showing a flexible washer used in the construction of the coil shown in the preceding views.

35 Similar reference characters refer to similar parts in each of the several views.

Referring first to Fig. 3, the coil is wound on a tube 1, usually of hard fiber, having no flanges at its ends. Before the winding 40 process is started, a washer 2 is attached to each end of the tube, each of which washers is of flexible material, such as unbleached muslin or other similar fabric, and each of which is preferably circular in form, as 45 shown in Fig. 5. The diameter of each washer is considerably greater than the diameter of the finished coil, for a reason which will appear hereinafter. Each washer is provided at its center with radially disposed slits 2^a of sufficient length to allow the 50 tube 1 to pass through the washer.

One of these washers is placed on each end of the tube with the triangular projec-

tions 2^b, due to the slits, pointing inwardly as shown in Fig. 4, and the washer is then 55 firmly attached to the tube by twine or like material 3 wound around these projections. Each washer then flares outwardly from one end of the tube, as illustrated in Fig. 4. The tube is then placed in a winding machine 60 and the first layer of wire is wound thereon, whereupon the machine is stopped and the insulation is scraped from several turns of the wire. A flexible lead 5 is then soldered to the bared wires, and the lead is 65 attached to the tube by twine 7 or similar material. The winding of the coil is then completed in the usual manner, a fine cotton thread being cross woven between each two 70 layers of wire to hold the wire in place and bind the coil together. A few extra turns of this thread are wound at each end of the wire part of the coil to form a cotton pad or wall 8 at each end of the coil. This winding process, consisting of the interweaving 75 of a cotton thread throughout the coil as a binder and the formation of the cotton heads or walls, is not original with us, but, on the other hand, may be applied by winding machines which are now in commercial 80 use. When the winding has been completed, another flexible lead 10 is soldered to a few turns of wire in the outermost layer.

During the winding of the coil, a number 85 of loops of twine 6 are preferably inserted between layers of wire, and these loops are used later to tie the flexible leads tightly against the cotton wall as shown in Fig. 2. By this means the leads are securely held in place for the subsequent application of the 90 cotton washer, and will withstand the strains incident to the handling and carrying 95 the coil by the leads.

After the winding of the coil has been completed, each washer 2 is drawn tightly 95 back over the corresponding end of the coil and bound firmly to the cylindrical surface of the coil by twine 9 or like material. Of course, suitable holes or slits are made in one of the washers to permit the leads 5 and 10 to project from the finished coil. Pressure may be applied to the ends of the coil, if desired, to force the leads into the cotton wall 8 so that the length of the coil 100 will not exceed the traverse of the winding machine. The coil is then complete so far 105

as construction is concerned, and is ready to be impregnated with an insulating compound or given any other finishing treatment that may be considered desirable.

5 The size of each washer 2 is preferably such as to permit it to be drawn back about one-half the length of the coil, as shown in Fig. 3, although it is only necessary that the washer should extend back far enough to 10 permit it to be secured to the coil by the twine 9.

The construction of coils by the method thus described has many advantages over the usual spool construction involving the 15 use of solid heads on the tube 1. The cost of the material for such heads, and the cost of making the same, are greater than the cost of the cotton washer employed in our invention. The application of the solid 20 heads in the spool construction requires a separate operation, as well as special tools, whereas in the practice of our invention, the fabric washer is applied by the winding machine operator, and is part of the coil 25 winding operation. Only one operation, viz., the setting up of the tube in the winding machine, is required for the complete winding, securing of leads and application of cotton washers and of the twine 9.

30 The usual spool construction has sometimes been eliminated by the use of a tape covering, but this scheme requires the removal of the coil from the winding machine, and the weaving of the tape through the 35 center of the coil; this process consumes considerably more material, and requires more labor, than the fabric washer method embodying our invention.

Another important advantage of the construction embodying our invention, is the 40 elimination of dead space in the coil. In spool wound coils, a certain amount of dead space exists due to the heads, or in a space required for housing flexible leads, or in 45 both places. All this dead space is eliminated in coils constructed in accordance with our invention, the leads being pressed into the cotton wall, if necessary, so as not to increase the normal length of the coil.

50 In the case of tape covered coils referred to above, the necessity for running the tape through the center of the coil, requires that the coil be made with an inside diameter greater than that required for a winding in 55 accordance with our invention. The elimination of this waste space makes it possible to keep the inside turns of the coil as close to the magnet core as clearance and insulation will permit, thus increasing the 60 number of turns for the same ohmic resistance, by decreasing the length of the average turn. This results in a higher degree of magnetization for a given core, which, in turn, permits a reduction in the 65 size of pole faces, or an increase in core pin

length, to maintain the same shunting characteristics, and will at the same time, cause the magnet to have greater power.

The elimination of the space required for the spool heads in spool construction, enables the length of iron in the magnetic structure to be reduced, so as to approximate the length of the winding. This feature increases the energization for a given length of iron, hence gives a greater density 75 of magnetization and for this reason permits a reduction in the size of pole faces or an increase in core pin lengths to obtain the same shunting characteristics. This feature also causes the magnet to have 80 greater power.

It can thus be seen that considerable waste space is eliminated by the construction of the coil in accordance with our invention, and that this elimination makes 85 possible the design of a more efficient magnet than has been possible heretofore.

Although we have herein shown and described only one method of coil construction embodying our invention, it is understood that various changes and modifications may be made therein within the scope of the appended claims without departing from the spirit and scope of our invention.

Having thus described our invention, what 95 we claim is:

1. The method of constructing a wire coil on a flangeless tube, which consists in attaching two flexible washers to the tube one at each end, winding the wire on the tube, 100 and subsequently wrapping each washer over the adjacent end and cylindrical surface of the coil and attaching it to the cylindrical surface of the coil.

2. The method of constructing a coil of 105 wire on a flangeless tube, which consists in slitting two flexible washers radially at the center so that the tube will pass through them, placing said washers on the tube one at each end with the projections due to said 110 slits pointing inwardly, attaching such projections to the tube, winding the wire on the tube, and subsequently wrapping each washer over the adjacent end and cylindrical surface of the coil and securing it to the 115 cylindrical surface of the coil.

3. The method of constructing a coil of wire on a flangeless tube, which consists in attaching two flexible washers to the tube one at each end, winding one layer of wire 120 on the tube, removing the insulation from several turns of said layer at one end and soldering a flexible lead to said turns, winding the balance of the wire on the tube, removing the insulation from several turns 125 at the end of the last layer of wire and soldering a flexible lead to said turns, and subsequently wrapping each washer over the adjacent end of the coil and attaching it to the cylindrical surface of the coil, said 130

flexible leads being brought out through a suitable hole in the adjacent washer near the outer rim of the coil.

4. The method of constructing a coil of wire on a flangeless tube, which consists in attaching two flexible washers to the tube one at each end, winding the wire on the tube with a few turns of insulating string at each end of each layer, and subsequently 10 wrapping each washer over the adjacent end

and cylindrical surface of the coil and binding it to the cylindrical surface.

In testimony whereof we affix our signatures in presence of two witnesses.

ARTHUR W. FISHER.
CLARENCE S. SNAVELY.
